CLAIM

The ornamental design for a charging station, as shown and described.

DESCRIPTION

FIG. 1 is a perspective view of a charging station showing our new design;

FIG. 2 is a front elevation view thereof;

FIG. 3 is a rear elevation view thereof;

FIG. 4 is a side elevation view thereof;

FIG. 5 is the opposite side of FIG. 4;

FIG. 6 is a bottom plan view of FIG. 1;

FIG. 7 is a top plan view thereof; and,

FIG. 8 is another perspective view thereof.
